UNITED STATES PATENT OFFICE.

FREDERICK W. PRESTON, OF YORK, PENNSYLVANIA, ASSIGNOR TO KEYSTONE ROOFING MANUFACTURING COMPANY, OF YORK, PENNSYLVANIA, A CORPORATION OF PENNSYLVANIA.

SHINGLE.

Application filed November 20, 1926. Serial No. 149,662.

My invention relates to roofing shingles of the composite type preferably made of flexible water-proof material and coated with slate or other suitable surfacing material embedded in the body of the material.

The principal object of the invention resides in the formation of the shingle in such a manner that when a plurality of shingles are laid upon the roof that a pleasing appearance will be presented and there will be a plurality of layers of the shingles thereby providing such undercovering as to prevent leakage therethrough.

A further object of the invention resides in providing a shingle having a body portion and a lateral extension, the lateral extension being adapted to overlie an adjacent shingle and being slit intermediate its ends whereby when a nail or other securing element is passed through the shingle the body portion will be depressed adjacent the shingle which is overlapped by the lateral extension and provide a tight joint or closure between adjacent shingles to prevent rain or snow from passing between the shingles.

Another object resides in so forming the shingles that when laid in roof formation one will be properly spaced relative to the other so as to leave spaces between the exposed portions of the shingles to assimilate the appearance of an ordinary shingle, means being provided whereby the upper end of the space will be securely closed to prevent leakage.

Still another object consists in forming the shingle in such a manner that when a plurality of the same are laid upon a roof there will be a double butt line for shadow line effect which will present a pleasing appearance and cause a more pronounced shingle effect than has been evident in the appearance of shingles of this character in the past.

With the above and other objects in view which will appear as the description proceeds my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a perspective showing the shingles arranged on a roof.

Fig. 2 is a top plan showing a plurality of shingles arranged upon a roof.

Fig. 3 is a transverse section on the line 3—3 of Fig. 2.

Fig. 4 is a perspective of one of the shingles.

Fig. 5 is a fragmental perspective showing the manner of laying the shingles with the lateral extension of one shingle overlapping the adjacent shingle, and

Fig. 6 is a perspective illustrating a slightly modified form of the invention.

In the drawings 1 indicates the body portion of the shingle having the lateral extension 2 at the upper edge the extension being provided with the slit 3 at the lower edge, intermediate the ends of the extension, but preferably in close proximity to the body portion 1 as more particularly illustrated in Fig. 4 of the drawings.

The shingles will be laid upon a roof in the manner as more clearly illustrated in Figs. 1, 2 and 3 of the drawings, the lower edges of the body portion of the shingle being on a line and the lateral extension of one shingle overlapping the body portion of the adjacent shingle, the slit 3 of the overlapping extension being positioned adjacent the end of that shingle which it overlaps so that a nail 4 may be driven through the shingle adjacent the lower edge of the extension, near the body portion of the shingle, and this will cause a depression of the shingle to secure a tight fit against the roof. As is quite clearly illustrated in the drawings the slit 3 is spaced a short distance from the inner edge of the body portion 1 so that when the shingles are laid upon a roof the space 5 will be provided between adjacent shingles to assimilate the effect of an ordinary shingle. The portion of the shingle which is depressed by the nail 4 forms a closure at the upper end of the space or slot 5 and thereby prevents water or other elements from entering beneath the shingle and a tight joint is provided.

At the point 6 in the particular embodiment of the invention illustrated, there will be three layers, at the point 7 five layers and at the point 8 four layers. This same arrangement or laying of the shingles will be continued throughout the roof and it will thus be seen that a heavy roofing is provided, relatively thick, so as to prevent leak-

age therethrough and greatly increasing the wearing qualities of the roof. In laying the shingles there is a double butt 9 and this presents a shadow line effect thereby adding to 5 the appearance of the roof.

In Fig. 6 I have shown a slightly modified form of shingle which consists of the body portion 10 and the lateral extension 11, in this form of shingle there being no slit provided 10 in the extension but instead, the shingles being flexible, when the nail 12 is driven in the position shown the shingle will be flexed downwardly, as shown, and provide a closure at the upper end of the space 13 between adjacent shingles.

From the above detail description it is thought that the advantages of my shingle will be clearly understood. When the shingles are laid there is a space left between 20 adjacent shingles and by providing the slits in the extensions a portion of the shingle is deflected or lowered to form a closure at the upper end of the space between the shingles and by doing this the rain and other elements 25 cannot possibly enter beneath the shingles. At the same time by having the overlapping extensions a plurality of layers of shingles are provided at practically all points over the roof the advantages of which can be readily appreciated. In the modified form of 30 the invention I have shown that, the shingles being flexible, it is not absolutely necessary that the slit be provided in the extension but the shingles may be flexed downwardly by 35 the driving of the nail.

Having fully described my invention what I claim as new and desire to secure by Letters Patent is:

1. A shingle having a body portion and a 40 lateral extension, the extension of one shingle being adapted to overlap the body portion of an adjacent shingle when laid upon a roof or the like with a space between the vertical edges of adjacent body portions and the bottom edge of the overlapping extension forming the top of the space.

2. A shingle having a body portion and a lateral extension, the extension of one shingle being adapted to overlap the body portion of 50 an adjacent shingle when laid upon a roof or the like with a space between the edges of adjacent body portions and a portion of the extension adjacent the space between the

body portions being depressed to form a closure at the top of the space. 55

3. A shingle having a body portion and a lateral extension, the extension of one shingle being adapted to overlap the body portion of an adjacent shingle when laid upon a roof or the like with a space between the edges of 60 adjacent body portions and a portion of the extension adjacent the space between the body portions being depressed by the insertion of a fastening element through the shingle to form a closure.

4. A shingle having a body portion and a lateral extension formed with a slit intermediate the ends thereof, the extension of one shingle being adapted to overlie the body portion of an adjacent shingle when laid 70 upon a roof or the like with the slit of the overlapping extension engaging the edge of the body portion of the overlapped shingle to form a space between adjacent edges of the body portions. 75

5. A shingle having a body portion and a lateral extension formed with a slit intermediate the ends thereof, the extension of one shingle being adapted to overlie the body portion of an adjacent shingle when laid 80 upon a roof or the like with the slit of the overlapping extension engaging the edge of the body portion of the overlapped shingle to form a space between adjacent edges of the body portions and a portion of the extension adjacent the slit being depressed to close the opening at the top of the space. 85

6. A shingle having a body portion and a lateral extension, the extension being formed and adapted to overlie the body portion of 90 an adjacent shingle when laid upon a roof or the like and to engage the same so as to position the adjacent vertical edges of the two shingles in spaced relation.

7. A shingle having a body portion and a lateral extension, the extension being formed and adapted to overlie the body portion of 95 an adjacent shingle when laid upon a roof or the like and having a portion to be depressed to engage the edge of the adjacent shingle so 100 as to position the adjacent vertical edges of the two shingles in spaced relation.

In testimony whereof I hereunto affix my signature.

FREDERICK W. PRESTON.
